UNITED STATES PATENT OFFICE.

WILLIAM JOHN SHORTEN, OF NASHVILLE, TENNESSEE.

CLASP.

1,073,714.

Specification of Letters Patent. Patented Sept. 23, 1913.

Application filed September 6, 1912. Serial No. 719,019.

To all whom it may concern:

Be it known that I, WILLIAM J. SHORTEN, a citizen of the United States, residing at Nashville, in the county of Davidson and 5 State of Tennessee, have invented a new and useful Clasp, of which the following is a specification.

The present invention relates to improvements in clasps, the primary object of the 10 invention being the provision of a novel form of clasp adapted to be used in connection with horses' collars, hame straps, belts, or in fact with any article that it is desired to quickly and permanently secure together, 15 yet in such a manner as to permit of the ready and easy release thereof, the present clasp being composed of two members one member of which is provided with spaced tongues, the other member being provided 20 with a receptacle for receiving one of the tongues of the first member, when the two members are interlocked, to retain the same against lateral movement.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the drawings—Figure 1 is a perspective view of the clasp separated and shown as attached to a hame. Fig. 2 is a longitudinal sectional view through the members of the clasp detached. Fig. 3 is a similar view with the members interlocked. Figs. 4 and 40 5 are respective top and bottom plan views of the female member. Figs. 6 and 7 are respectively top and bottom plan views of the male member of the clasp. Fig. 8 is a plan view of the male member having slots 45 instead of teeth.

Referring to the drawings, the numerals 1 and 1' designate the two hame members, each one of which is provided with the respective straps 2 and 2' whereby the respective female member 3 and male members of the clasp are properly connected, the straps 2 and 2' being threaded through the bails or open lugs 5 and 6 respectively, carried by their respective members 3 and 50 4. The member 3 is constructed from a single piece of metal and is bent upon itself

to form the lower member 7 which is provided with the guiding tongue 8 and the upper member 9 which is provided with the slightly tapered and curved locking terminal 10, said terminal 10 being provided with the finger engaging portions 10' which form an enlarged head and project beyond the outer line of the member, the under surface of the tongue 10 being provided with 60 the single tooth 11 which forms a spring lock for the member. The tongue 8 is known as the guiding tongue, while the tongue 9 is the locking tongue of this member. The tension of the locking tongue 9 65 is toward the tongue 8 so that the tooth 11 will always have a tension toward the tongue 8, the purpose of which will presently appear.

The male member of the clasp, is made 70 in the form of a curved tongue and is provided with the entering point 12 and upon the upper surface with a plurality of teeth 13 which are disposed to co-act with the single tooth 11 of the locking tongue 9 of 75 the female member when the members are in the position as shown in Fig. 3 to thus lock the members in assembled position, the guiding tongue 8 when in such position being seated within the pocket 14 carried 80 by the member 4 upon the opposite side to the teeth 13. By this means the tongue 8 retains the members against lateral movement while the tension upon the locking tongue 9 pulls the tooth 11 into engagement 85 with either one of the teeth 13. By providing the entering point 12 upon the male member 4, the members are readily locked and moved from the position as shown in Fig. 2 to that shown in Fig. 3. 90 By providing the finger gripping portions 10' upon the member 9, the said portions being so disposed as to project beyond opposite sides of the member 4 when assembled, the resilient locking tongue 9 may be 95 readily disengaged so that the parts may be moved from the position shown in Fig. 3 to that shown in Fig. 2.

As shown in Fig. 8, the member 4' is provided with transverse slots or openings 105 13' which correspond to the teeth 13 of the member 4 and are for co-action with the tooth 11 of the female member.

From the foregoing description, taken in connection with the drawings it is evident 110 that with a clasp constructed according to and embodying the present invention, that

a very practical device is provided for use in connection with the free ends of belts, the connecting straps of hame, and in fact any medium that it is desired to quickly 5 connect and disconnect. By means of the legs 5 and 6, the members may be stitched or otherwise secured to a horse collar or to the top of a shoe to form a fastening device.

10 What is claimed is:

A clasp, composed of two members for interlocking engagement, one member being a relatively rigid curved plate having a plurality of transversely disposed teeth 15 upon one face and a projecting portion upon the opposite face extending from one end to a point near the center of the plate, said projecting portion being provided with a relatively narrow slot disposed parallel to the adjacent face of the plate; and 20

the other member having two resilient tongues disposed in spaced relation with a normal tension toward each other, one tongue being narrower at its free end than the other tongue for insertion within the 25 slot of the projecting portion of the first member, while the free end of the other tongue is provided with a tooth to engage one of the teeth of the first member when the plate of the first member is disposed between the resilient tongue of the second member. 30

In testimony that I claim the foregoing as my own, I have hereto affixed my signature in the presence of two witnesses.

WILLIAM JOHN SHORTEN.
